UNITED STATES PATENT OFFICE

2,592,504

CHAISE-LONGUE BED COMBINATION

Edward E. Woller, Kenosha, Wis., assignor to
Simmons Company, New York, N. Y., a corpora-
tion of Delaware

Application July 26, 1947, Serial No. 763,869

1 Claim. (Cl. 5—47)

1

The main objects of this invention are to provide an improved arrangement of spring-actuated arms for facilitating the shifting of the two sections of a lounge between their normal lounge positions and their extended coplanar bed positions; to provide improved spring-actuated arms of this kind which permit the seat section of said lounge in either of its positions to be elevated at the front thereof in order to afford access to the bedding-box base on which said sections are shiftably mounted; and to provide improved spring-actuated arms for lounge sections of this kind which require a minimum number and simple arrangement of parts.

In the accompanying drawings,

Fig. 1 is a plan view of a chaise longue equipped with spring-actuated arms constructed in accordance with this invention. Portions of the upholstery and its support are broken away in order to more clearly show parts of the spring-actuated arms;

Fig. 2 is an enlarged fragmentary detail taken on the line 2—2 of Fig. 1;

Fig. 3 is a side elevation, as viewed from the plane of the line 3—3 of Fig. 1, showing the chaise longue sections in their coplanar bed position. A small portion of one of the sides of the supporting base is broken away so as to more clearly indicate the parts of the spring-actuated arms; and

Fig. 4 is a similar view but showing the back section in its normal elevated position and with the seat section elevated at the forward end for the purpose of obtaining access to the bedding box.

A chaise longue embodying a spring-actuated arm mechanism constructed in accordance with this invention comprises a supporting frame 5 on which seat and back sections 6 and 7 are shiftably mounted by means of supporting elements 8, the shifting of which sections is facilitated by an improved spring-actuated adjusting arm mechanism 9.

The supporting frame 5 comprises a base 10 and a pair of ends 11 and 12. The base 10 is a box-like structure supported on legs 13 and constitutes a compartment for bedding. As herein shown, this base 10 is comparatively narrow and extends forwardly of the ends 11 and 12 a distance greater than the front-to-rear dimension of said ends 11 and 12. Along the inner face of the lateral sides of the base 10, adjacent the top edges thereof, are secured angle bars 14 which provide support for the seat and back section supporting elements 8 as will appear more clearly hereinafter.

2

The ends 11 and 12 may be of any suitable construction, and are of the normal height, with a front-to-back dimension characteristic of furniture of this kind.

The seat and back sections 6 and 7 also are of a more or less conventional construction. The seat section comprises a frame 15 whereon is mounted suitable spring-supported upholstery 16. Similarly, the back section 7 comprises a supporting frame 17 whereon is mounted suitable spring-supported upholstery 18. Being a chaise longue, the seat section 6 is of a length slightly less than the over-all length of the base 10 over which it is superimposed. In this structure the seat section serves as a closure for the bedding compartment in the base 10. The back section 7 is of a height considerably less than the front-to-back dimension of the ends 11 and 12.

The supporting elements 8, for the seat and back sections 6 and 7, comprise a pair of upright standards 19 and pairs of brackets 20 and 21. Each of the standards 19 is integral with a plate 22 of angle construction which rests upon an angle bar 14 on the base 10. A pair of pins 23 engage the under side of the horizontal flange of the bar 14 so that the standard 19 is not displaceable but may be shifted along the bar 14 to permit the appropriate movements of the seat and back sections 6 and 7 to alter their relationship from that of a lounge to that of a bed, and vice versa.

The pairs of brackets 20 and 21 are of nearly identical form. They are angular shaped, somewhat in the nature of a boomerang. The pair 20 are secured adjacent the rear ends of the lateral sides of the seat-section supporting frame 15. The pair 21 are rigidly secured adjacent the lower corners of the sides of the back-section supporting frame 17. At their upper adjacent ends the pairs of brackets 20 and 21 are pivoted at 24 and 25 respectively to the upper ends of the standards 19. The mounting of the brackets 20 and 21 on the respective seat and back sections 6 and 7 and the location of the pivots 24 and 25 are such that the lower forward edge of the upholstery 18 and the rear upper edge of the upholstery 16 closely abut. Therefore, there is practically no gap in the continuity of the upholstery of these two sections when in their coplanar positions, as rather clearly indicated at 26 in Fig. 3.

The spring-actuated arm mechanism 9 whereby the shifting of the seat and back sections 6 and 7 is facilitated, comprises a pair of back-section

arms 27 and a pair of seat-section arms 28 between which is connected a tension spring 29.

The arms 27 are anchored to a shaft or rod 30 pivoted at its ends on the base 10 near the upper rear edges of the sides thereof. The upper ends of the arms 27 are pivoted at 31 to the sides of the back-section supporting frame 17, preferably to the brackets 21. Intermediate the points of attachment of the arms 27 to the shaft 30 a short arm 32 is connected. This arm 32 with the shaft 30 and the arms 27 constitute, in effect, a bell crank.

The arms 28 at their lower ends are pivotally mounted on trunnion plates 33. These plates are secured to the inner sides of the base 10 near the bottom of the base and at points inwardly from the front face of the frame ends 11 and 12, so that the upper free ends of the arms 28, when the arms are in their depressed positions, are rearwardly of the front face of the frame ends 11 and 12. At their upper ends the arms 28 are provided with rollers 34 which engage tracks 35 formed on the under sides of the seat-section frame 15.

An equalizer rod 36 extends between the arms 28 near their upper ends and is rigidly connected thereto in order to maintain the arms 28 in alignment and to assure their movement in unison.

The spring 29 is connected to the lower end of the short arm 32 and to the rod 36 intermediate the arms 28. This spring serves the dual purpose of applying pull to both pairs of arms 27 and 28. The spring 29 acting on the arms 27 normally tends to swing them rearwardly and into their upright positions. Similarly, the spring 29 tends to swing the arms 28 upwardly and rearwardly. It will be apparent from Figure 4 of the drawings that the spring 29 remains disposed closely beneath the seat section 6 throughout the swinging movement of the seat section about the hinge axis 24, and that the connection of the spring to the equalizer rod 36 constitutes the arms 28 as levers of the third order for urging the seat section upwardly. With this arrangement, substantially the entire volume of the bedding compartment is available as useable storage space, there being no substantial interference by the spring 29.

The tension on the spring 29 is very greatly increased when the seat and back sections 6 and 7 are shifted from their lounge positions to their coplanar bed positions for the reason that, as shown in Fig. 3, the arms 27 move forwardly about the pivot of the shaft 30. Hence, when it is desired to shift the sections so as to elevate the back section 7 the spring facilitates the return of the back section to its normal upright position.

When it is desired to have access to the bedding compartment base 10 the spring 19 facilitates the raising of the forward end of the seat section 6, as most clearly shown in Fig. 4. Such an elevating of the seat section 6 may be effected when the sections are in their lounge positions,

as shown in Fig. 4, or when in their extended bed positions, as shown in Fig. 3.

Rollers 37 on the underside of the seat section frame 15 rest on the angle bars 14 to facilitate movement of the seat section horizontally between its extreme positions. A stop 38 on the sides of the seat-section frame 15 engage the rollers 34 on the arms 28 and limit the upward swing of the seat section 6.

Variations and modifications in the details of structure and arrangement of the parts may be resorted to within the spirit and coverage of the appended claim.

I claim:

15. A convertible lounge comprising a supporting frame providing a bedding box, a pair of standards reciprocably mounted on said frame for forward and rearward movement thereon, a seat section and a normally upright back section hinged to said standards, said seat section overlying said box, in movable contact with said frame, said sections being adjustable from their normal seat and back positions to co-planar positions on said frame to form a bed, said seat section in either position being swingable upwardly at its front end to afford access to said box, a bell crank lever pivoted on said frame at the rear thereof below said back section, one arm of said crank extending upwardly and being pivotally connected to said back section at a point intermediate its height, the other arm of said crank extending downwardly from the crank pivot, a pair of aligned upwardly- and forwardly-extending arms pivoted at their lower ends respectively to opposite sides of said frame forwardly of said bell crank, an equalizer rod extending between and rigidly connected to said arms adjacent their upper ends for maintaining the alignment of said arms, said last-mentioned arms being engageable at their upper ends with the underside of said seat section, and a tension spring connecting said downwardly extending arm of said bell crank and said equalizer rod, said spring constituting said seat-section engaging arms as third class levers for urging the front end of said seat section upwardly and also tending to swing said upwardly-extending arm of said bell crank rearwardly for counterbalancing the weight of said back section to facilitate adjustment of said sections.

EDWARD E. WOLLER.
